(57) **CLAIM**

We claim the ornamental design for the digital information display device, as shown and described.

DESCRIPTION

FIG. 1 is the front perspective view of the digital information display device showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof;

FIG. 7 is the bottom plan view thereof;

FIG. 8 is a perspective view thereof showing one configuration of the device on an unclaimed support;

FIG. 9 is a perspective view thereof showing the device in a folded position;

FIG. 10 is a perspective view thereof showing the device in a folded position on an unclaimed support;

FIG. 11 is a perspective view thereof showing the device in an “open” position on an unclaimed support;

FIG. 12 is an enlarged view of the left hand end of the bottom plan view of FIG. 7; and,

FIG. 13 is an enlarged view of the right hand end of the bottom plan view of FIG. 7.

The short dash-dash broken lines showing of portions of the digital information display device in the figures form no part of the claimed design. In FIGS. 7, 12 and 13, the alternate dot-dash broken lines encircling a portion of the claimed design are for illustrating the enlargement and form no part of the claimed design. in FIGS. 8, 10 and 11, the dot-dot-dash broken lines showing of the support are for the purpose of illustrating environmental structure and form no part of the claimed design.
